UNITED STATES PATENT OFFICE.

MATHER W. SHERWOOD, OF FRANKLIN, PENNSYLVANIA, ASSIGNOR TO CHICAGO PNEUMATIC TOOL COMPANY, OF CHICAGO, ILLINOIS, A CORPORATION OF NEW JERSEY.

PNEUMATIC TOOL.

1,243,770.

Specification of Letters Patent.

Patented Oct. 23, 1917.

Application filed February 24, 1914. Serial N. 820,548.

To all whom it may concern:

Be it known that I, MATHER W. SHERWOOD, a citizen of the United States, residing at Franklin, in the county of Venango and State of Pennsylvania, have invented certain new and useful Improvements in Pneumatic Tools, of which the following is a specification.

My invention relates to tools operated by a motive fluid, usually compressed air and therefore commonly called pneumatic tools. The object of my invention is to provide a simple and efficient construction of tool embodying means for rotating the working tool through the medium of the motive fluid employed in the operation of the tool. In the present instance my invention is embodied in a type of pneumatic tool known as a hand drill employed more particularly as a rock drill and the working tool is consequently a drill bit which is positively operated during the drilling operation by the motive fluid.

In the drawings, Figure 1 is a central longitudinal section of a hand drill embodying my invention but showing the handle mostly in elevation; Figs. 2, 3 and 4 are sections on the lines 2-2, 3-3 and 4-4 of Fig. 1; Fig. 5 an elevation of one of the ratchet rings; Fig. 6 an edge view thereof; Fig. 7 an elevation of the locking ratchet ring; Fig. 8 an edge view thereof, Fig. 9 an elevation of the inner end of the drill chuck, and Fig. 10 a section on the line 10-10 of Fig. 1.

For the purposes of a clear and definite description of my invention I have shown the same embodied in a type of drill known as a hand drill but it will be understood that my invention is not to be limited thereto and that I contemplate using the same wherever applicable.

Referring to the particular embodiment of my invention as herein shown the drill comprises a main cylinder 1 having a piston chamber 2, a piston 3 reciprocable therein and having a hammering portion or stem 3^a, a striking piece or anvil 4, a drill bit 5, a front head 6, a rotatable drill chuck or socket 7 and a suitable handle 8 secured to the cylinder by the side rods 9 which also serve to clamp and hold the front head. The piston chamber 2 has communication with the live motive fluid entering through the inlet connection 10 through suitable ports

and passages governed by a distributing valve which is here in the form of a ball 11. The piston chamber is also in communication with the atmosphere through suitable ports and passages, all of which ports and passages will be hereinafter more particularly described.

Referring to the rotary mounting of the drill chuck and the means for positively rotating the same, such chuck is provided with a central bore the outer end of which projecting through the front head is of a shape to receive the angular shank of the drill bit. This chuck fits and rotates within the head 6 and is provided at its inner edge with two opposite slots 7^a.

The means for positively rotating the chuck are contained within a casing which is interposed between the front end of the main cylinder and the front head 6 and is clamped therebetween by means of the side rods 9 in the manner clearly indicated in Fig. 4. This casing has a central portion 12 provided with a central bore whose axis is coincident with the axis of the longitudinal axis of the main cylinder and which accommodates the working parts of the mechanism. The casing is also provided at diametrically opposite sides with two similar rotation cylinders 13 and 14. By preference the entire casing is made in two separable parts or sections which are held together in suitable manner as by means of the bolts 15. Within the rotation cylinders 13 and 14 are arranged two pairs of pistons 16 and 17 which are preferably hollow and of rectangular section and also independent of each other except that they move in unison in the manner hereinafter explained.

For the purpose of reciprocating the pistons 16 and 17 by means of the motive fluid of the tool the opposite ends of the rotation cylinders 13 and 14 are connected at their opposite ends with the opposite ends of the main piston chamber 2 in such manner that when the motive fluid is admitted to one end of a cylinder the motive fluid will be simultaneously admitted to the opposite end of the other cylinder. In the present instance the main piston chamber 2 communicates near its rearward end with two similar ports and passages 18 extending longitudinally of the cylinder and after passing partially through the casing 12 enter the left-hand end of the rotation cylinder 13 and the right- 110

hand end of rotation cylinder 14 when the parts are viewed as in section 2. The front end of the piston chamber communicates through the ports and passages 19 with the 5 other ends of the rotation cylinders 13 and 14, that is to say the front end of the main piston chamber communicates by said passages 19 with the right-hand end of rotation cylinder 13 and with the left-hand end of 10 rotation cylinder 14 when the parts are viewed as in Fig. 2.

When the parts are in the relative position shown in Fig. 1 with the ball-valve in its left-hand position, the live motive fluid 15 enters through the connection 10 through the port 20 and passages 21 and 22 into the front end of the main piston chamber with the result that the piston 3 is returned to its rearward position. The live motive fluid at 20 the front end of the main piston chamber passes through the ports 19 to the ends of the rotation cylinders 13 and 14, driving the pistons 16 and 17 to the opposite ends of 25 said cylinders and operating the chucking driving mechanism in the manner herein-after explained. When the ball-valve 11 moves to its right-hand position the live motive fluid is admitted to the rear end of the main piston chamber with the result 30 that the live motive fluid passes through the ports and passages 18 to the other ends of the rotation cylinders 13 and 14 and drives the pistons 16 and 17 to the opposite ends of their piston chambers. When the valve 35 is in said right-hand position the live motive fluid enters through the connection 10, through the ports 23 and 24 into the rear end of the main piston chamber.

A driven ratchet ring 25 which is shown 40 in detail in Figs. 5 and 6 fits upon the inner edge of the drill chuck, the slots 7^a of which receive the opposite similarly-shaped lugs 25^a. This ratchet ring co-operates with a driving ratchet ring 26, the ratchet teeth 45 of the two rings being adjacent each other in co-operative relationship. This driving ring is provided at diametrically opposite sides with radial operating arms 27 and 28 projecting through the slots or openings 29 50 and 30 extending into the two rotation cylinders 13 and 14 respectively. The arm 27 projects into the rotation cylinder 13 and between the two pistons 16 while the other arm 28 projects into the rotation cylinder 55 14 between the two pistons 17. As the result of this construction and arrangement the pistons 16 and 17 by their reciprocations cause an oscillating movement of the driving ratchet ring 26. When this ring is 60 driven in one direction its ratchet teeth will drivingly engage the driven ring 25 which being in engagement with the drill chuck causes a rotation of the latter. When the ratchet ring 26 is moved in the opposite 65 direction its ratchet teeth will ride upon

the teeth of the driven ring and at the end of such movement will obtain a new engagement therewith, ready for the next reciprocation of the pistons 16 and 17. The driving and the driven rings are held in co-operative relationship with yielding pressure by suitable means such as the coiled springs 31 interposed between the driving ring and a part of the recess formed in the interior of the casing 12 to receive said 75 rings.

By preference and as herein shown a locking ratchet ring 32 is employed the same being located within and concentric of the driving ring 26 as clearly indicated in Figs. 3 and 4. This locking ring has on its outer edge ratchet teeth which engage with the ratchet teeth on the driven ring 25. The locking ring is a stationary one and in order to hold it thus it is provided at opposite sides with lugs 32^a which engage in sockets 33 in the interior of the casing 12. This ratchet ring while stationary as concerns rotation has a slight movement longitudinally of the tool being held in yielding 80 engagement with the driven ring in suitable manner as by means of the coiled springs 34 interposed between it and the body of the casing 12.

As hereinbefore stated the casing which 95 contains the rotation mechanism is clamped between the main cylinder and the front head of the tool by means of the side bolts 9. In practice and as shown in Fig. 4 the front end of the cylinder is reduced in 100 diameter and extends entirely through the casing 12, the reduction in diameter of the cylinder producing a shoulder 35 against which the rear end of such casing abuts. This reduced front end of the cylinder contains a bushing 36 within which the front or striking end of the piston 3 reciprocates and which also holds the striking piece or anvil 4. The rear end of the drill chuck is of 105 enlarged diameter so as to fit the exterior of the reduced end of the main cylinder, such chuck being mounted to rotate between such cylinder end and the rear end of the front head 6. This head is arranged to interlock with the casing 12 for which purpose such 110 casing is provided with a flange 37 fitting into a corresponding counter bore in the rear end of the front head.

Describing a complete cycle of operation of the tool and starting with the parts in 115 the position shown in Fig. 1, the motive fluid is delivered through the connection 10, port 20 and passages 21 and 22 to the front end of the main piston chamber, causing the piston 3 to be driven rearwardly. When the piston is in the position shown in Fig. 1 the rear end of the piston chamber is at exhaust through the rear exhaust groove 38 and exhaust port 39 which communicates with the atmosphere through an exhaust 120 125 130

shut-off valve hereinafter described. The piston in its rearward movement uncovers the front exhaust groove 38 exhausting the front-end of the piston chamber and the 5 live motive fluid in the rear corners of the valve chamber acts upon the ball-valve forcing the latter to its right-hand position. At this time the front end of the piston chamber is at exhaust through the front 10 exhaust groove 38 and exhaust port 39 and the live motive fluid is admitted through the supply connection 10 and ports 23 and 24 to the rear end of the piston chamber so as to drive the piston to the position shown 15 in Fig. 1. At this time, that is with the live motive fluid in the rear end of the piston chamber, a portion of such fluid will pass through the ports 18 to the one end of the rotation cylinder 13 and other end of 20 the rotation cylinder 14, thereby driving their respective pistons to the opposite ends of said rotation cylinders or chambers and locking the driving ratchet ring in the manner hereinbefore explained. At such time 25 the opposite ends of these rotation cylinders are open to exhaust through the ports and passages 19 and the front exhaust groove 38 and front exhaust port 39. The piston 3 in its forward reciprocation delivers 30 its blow upon the anvil 4 which in turn delivers the blow upon the inner end of the drill bit 5. When the piston 3 in its forward movement has uncovered the rear exhaust groove 38, the motive fluid at that 35 end of the piston chamber will be exhausted and simultaneously live motive fluid in the front end of the valve chamber exerting its force through the passages 21 and 22 will act upon the ball-valve and drive it to its 40 left-hand position. At this time the live motive fluid will pass through the ports and passages 19 to their end of the rotation cylinders or piston chambers so as to drive or rock the driving ring in the other direction. 45 The ball-valve is arranged in a cage 11^a which has openings 11^b for the passage of the live motive fluid. It will be understood that these openings are somewhat restricted as compared with the passages leading from 50 the valve cage to the opposite ends of the main piston chamber with the result that the described valve operations can take place.

As hereinbefore stated the two exhaust 55 grooves 38 communicate with similar exhaust ports 39. These exhaust ports in turn communicate through corresponding registering ports of a shell valve 40 with the interior thereof, such valve being open at 60 one end to the atmosphere. This valve is arranged to oscillate in a chamber 41 extending longitudinally of the piston chamber 2, such valve acting as an exhaust shut-off. This valve is adapted to be manually 65 manipulated by means of a handle 42 se-

cured to the solid end of the valve and arranged to move through the slot 43 in the outer wall of the chamber 41. This slot is provided along one edge with a series of notches 43^a into which the handle is sprung 70 pressed and thereby held in different adjusted positions. As shown a spring 44 is interposed between a pin or stud 45 rotatably connected with the solid end of the valve and the plug 46 at the outer end of 75 the chamber 41. According to this construction the valve 40 may be oscillated by means of the handle 42 so as to bring the exhaust ports 39 out of register with the ports in the valve, thereby shutting off the exhaust. 80 When the handle 42 is released the spring 44 will move the valve 40 slightly longitudinally into engagement with one of the notches 43^a. In restoring the valve 40 to open exhaust position the reverse operation 85 takes place, that is the valve 40 is moved slightly rearwardly to bring its handle out of the notch 43^a and is then swung to open position. When this position is reached and the operator's hold on the handle 42 is released 90 the spring 44 will force such handle to one of the other notches 43^a thereby retaining such valve in its open exhaust position.

The exhaust shut-off valve 40 is provided 95 for the purpose of enabling the motive fluid to be discharged through the drill bit and to thereby blow out the cuttings in the bottom of the hole made by the bit. As shown this bit is provided with a central 100 passage 5^a which communicates with a central passage 4^a in the anvil 4. The piston stem or extension 3^a is provided with one or more longitudinal grooves or flattenings 3^b in order to permit the motive fluid at the 105 front end of the piston chamber to pass by such stem and pass through the passages 4^a and 5^a to the cutting end of the drill bit or steel. It will be understood that the passage 4^a is of limited carrying capacity in order 110 not to interfere with the reciprocations of the piston 3. Every time the motive fluid is admitted to the front end of the main piston chamber a portion thereof thus passes down through the anvil and through the 115 hollow steel for the purpose stated.

In the event that the supply of air delivered to the cutting end of the drill bit is insufficient so that the hole is not being properly cleared of chips or cuttings, the exhaust 120 valve 40 is closed. The piston 3 will travel rearwardly but upon reaching its rearward position, there being no complete release of the motive fluid to throw the ball-valve the air will continue to flow through the anvil 125 and through the drill bit to eject the chips or cuttings. By these means the piston 3 is rendered inoperative and a direct and continuous supply of air is delivered through the tool to the cutting end of the drill bit. 130

I do not herein claim the drill bit cleansing feature hereinbefore described but have made the same the subject matter of divisional application filed on March 12, 1915, 5 Serial No. 13,586.

I claim:

1. The combination of a reciprocating type of drilling engine operated by motive fluid and having a rotatable drill chuck, and 10 means for rotating the chuck including a driven ratchet ring removably secured to the inner end of the chuck and having a bearing flange, a driving ratchet ring coöperating with the driven ring, a casing containing 15 said rings and providing a bearing for the flange of the first-named ring, and fluid pressure mechanism for oscillating the driving ring.
2. The combination of a reciprocating 20 type of drilling engine operated by motive fluid and having a rotatable drill chuck, and means for rotating the chuck comprising a driven ratchet ring removably secured to the inner end of the chuck and having a bearing 25 flange, a driving ratchet ring coöperating with the driven ring, a casing containing said rings and providing a bearing for the flange of the first-named ring, a stationary locking ring coöperating with the 30 driven ring, and fluid pressure mechanism for oscillating the driving ring.
3. The combination of a reciprocating 35 type of drilling engine operated by motive fluid including the cylinder and a rotatable drill chuck at the front end thereof, and means for rotating the chuck comprising a driven ratchet ring detachably connected with the inner end of the chuck and arranged in a plane at right angles to the 40 axis of rotation of the chuck, a driving ratchet ring coöperating with the driven ring, a stationary locking ring coöperating with the driven ring and arranged concentric thereof, a casing 45 arranged at the front end of the cylinder and having annular cavities to receive said rings, springs 31 and 34 in said cavities behind the driving

and locking rings for pressing them into engagement with the driven ring, and fluid pressure mechanism independent of the 50 drill-actuating piston for oscillating the driving ring.

4. The combination with a drilling engine including its cylinder and front head, said cylinder having a reduced front end, of a 55 drill chuck mounted to rotate in the head and having an inner bearing upon such reduced end of the cylinder, a casing fitting upon said reduced end and interposed between the main body of the cylinder and the front head, and fluid pressure operated mechanism contained within the casing for rotating the chuck.

5. The combination with a drilling engine including its cylinder and front head, 65 said cylinder having a reduced front end, of a drill chuck mounted to rotate in the head and having an inner bearing upon such reduced end of the cylinder, a casing fitting upon said reduced end and interposed between 70 the main body of the cylinder and the front head, and fluid pressure operated mechanism contained within the casing for rotating the chuck, said casing being formed in two detachable sections.

6. The combination with a drilling engine including its cylinder and front head, of a 80 drill chuck mounted to rotate in the head, a casing interposed between the head and cylinder, the cylinder having an extension projecting through the casing, a driven ratchet ring detachably connected to the chuck, a driving ratchet ring arranged to coöperate 85 with the driven ring, and a locking ring coöperating with the driven ring, said driven ring and locking ring being mounted within the casing and directly on the cylinder extension, and the driving ring being mounted on the locking ring.

MATHER W. SHERWOOD.
